UNITED STATES PATENT OFFICE.

HOWARD O. McMILLAN, OF MINNEAPOLIS, MINNESOTA.

FORM TIE FOR CONCRETE FORMS.

Application filed November 19, 1925. Serial No. 70,018.

This invention relates to a tie or clamp device for concrete forms. Concrete is now largely used for building purposes and, when walls or columns are made, a form is built comprising spaced walls between which the concrete is poured. It is necessary that these walls be firmly secured in position so that they will not spread under the weight of the wet concrete and it is the common practice to tie walls together with various kinds of ties. It is also desirable to have a tie which can be adjusted so that the walls can be drawn up to proper position if there is any tendency to spread.

It is an object of this invention to provide a simple and inexpensive form tie which can conveniently be placed in position and easily and quickly placed and held under the desired tension to hold the walls in proper position.

It is a further object of the invention to provide such a tie having members to engage the longitudinal members which are generally used extending along the exterior of the wall and also comprising a strip received in said first mentioned members, said strip and first mentioned members having a take-up means for tensioning said strip so that the walls are held in proper position.

It is also an object of the invention to provide a form tie comprising a flat strip of metal having spaced elongated slots arranged longitudinally therein, which strip passes through and between the walls of the form and is received in members engaging the exterior of the form having spaced elongated slots extending transversely therethrough, and wedge members adapted to extend through said latter slots and the slots in said strip, the slots in said strip and member being differently spaced so that said strip can be drawn and placed under tension by said wedges.

It is a further object of the invention to provide a form tie, as set forth in the preceding paragraph, in which wedges may also be used in said strip at the inner side of the walls to form spacing means.

It is still another object of the invention to provide a form tie comprising a slotted strip and member at the exterior of the form having slots and wedges adapted to be inserted therethrough and through the slots in said strip, which members may be attached to and conveniently used with the

well known metal panel type of form for concrete walls.

These and other objects and advantages of the invention will be fully set forth in the following description made in connection with the accompanying drawings in which like reference characters refer to the same parts throughout the different views, and in which,

Fig. 1 is a horizontal section through a portion of the concrete form showing the invention applied thereto;

Fig. 2 is a view of one of the members of the device, as seen from the right of Fig. 1;

Fig. 3 is a vertical section through a form showing the invention applied thereto;

Fig. 4 is a vertical section through one side of the form showing a modified form of the device;

Fig. 5 is a view in side elevation of the device shown in Fig. 4 and some of the form members;

Fig. 6 is a view in horizontal section of a form showing a still further modified form of the device;

Fig. 7 is a vertical section taken on the line 7—7 of Fig. 6, as indicated by the arrows;

Fig. 8 is an end view of the device shown in Fig. 6, Figs. 7 and 8 being on an enlarged scale;

Fig. 9 is a perspective view of a form made of metal panels showing various forms of the invention applied thereto;

Fig. 10 is a vertical section taken on the line 10—10 of Fig. 9, as indicated by the arrows;

Fig. 11 is a vertical section taken on the line 11—11 of Fig. 9, as indicated by the arrows;

Fig. 12 is a vertical section taken on the line 12—12 of Fig. 11; and Fig. 13 is a horizontal section taken on the line 13—13 of Fig. 9, as indicated by the arrows.

Referring to the drawings, particularly to Figs. 1, 2 and 3, a portion of a form for a concrete wall is shown comprising the side walls 15 which extend in parallel relation. While these walls may be formed of wooden or metal members, in the embodiment of the invention illustrated in Figs. 1 and 2, they are represented as being formed of superposed horizontally extending boards. These boards have vertical timbers 16 extending therealong at their outer sides illustrates in

Figs. 1 to 3 as 2 x 4's. In accordance with the present invention a thin metal strip 17 is used having formed therein a series of elongated rectangular slots 17^a disposed

5 longitudinally of said strip. The strip 17 extends through and between the walls 15, either between the boards thereof or through openings in the boards and the ends of said strip are received in members 18 at the outer 10 side of the board. The members 18 each have an arm 18^a formed as a right angle fitting around one corner of the timber 16 and also have body portions 18^b disposed at a right angle to the arm 18^a and extending 15 along one side of the timber 16. The arm 18^a is formed as a flange with a central outer rib and said flange has a hole 18^c at one side thereof adapted to receive a nail 19 driven into the timber 16. The portion 18^b has a 20 passage extending therethrough shown as a narrow slot 18^e in which is received the ends of the strip 17. The portions 18^b also have elongated slots 18^d extending vertically therethrough adapted to align with the slots 25 17^a in strip 17. The slots 18^e are spaced a greater distance apart than the slots 17^a and while the slots may be variously spaced, in the embodiment of the invention illustrated, the slots 18^e are spaced about three times the 30 distance of the slots 17^a. Wedges 20 are provided of a width and thickness adapted to be received in the slots 18^d, pass therethrough and through the slots 17^a in strip 17. The wedges 20, preferably, are provided 35 with holes 20^a at their wide ends by means of which they can be strung on a wire for convenience in handling and transporting. Similar wedges 20 may also be driven into the slots 17^a in contact with the inner surfaces 40 of the walls 15, as shown in Figs. 1 and 2.

In operation, the strip 17 will be placed in the form and members 18 applied to the timber 16. A wedge will then be inserted in one of the slots 18^d in members 18 and driven downwardly therein. The edge of the wedge will act on the end of slot 17^a, engage and tend to move strip 17 lengthwise, thus tensioning said strip and pulling the members 18, as well as members 16, together. 45 The walls of the form can thus be drawn up very tight. If the wedge 20 used is driven sufficiently in to bring the ends of the slots 17^a and 18^d into alinement, the end of another slot 17^a will be in alinement with the 50 other rod 18^d and another wedge can be started and driven into this slot. A successive, or step-by-step take-up means is thus provided for the strip 17. The walls of the form can thus be tightly clamped in position and can be drawn up to the proper position if they spread. The wedges 20, at the inner surface of the walls 15 will be placed in position after the walls are tightly drawn up and will act as spacing means for the 55 wall holding them in proper spaced relation.

After the concrete is set, the wedges 20 will be removed and the members 18 will be moved from the strip 17. The ends of strip 17 can be bent down along the outside of the wall or broken off, the strips 17 remaining in the wall. It will, of course, be necessary to tension the strip 17 only at one end. The member 18 may be made similar, however, so as to eliminate the necessity of different kinds of parts.

In Figs. 4 and 5, a form is shown having the walls 15 and timbers 16, together with additional slightly spaced bracing timbers 21 extending horizontally along the form at the outer side of timber 16. The timbers 21 are 80 illustrated as the well known 2 x 4 timbers. The strip 17 is provided, as shown in Figs. 1 and 3, extending through and between the walls of the form and between the timbers 21, and a member 22 receives the end of strip 17. The member 22 is shown as having a circular flange 22^a extending across the outer surface of timbers 21, which flange has a plurality of holes adapted to receive nails 24 driven into timbers 21. The member 22 90 has a central portion projecting at right angles to flange 22^a having a passage 22^b therethrough shown as a narrow slot which receives the end of the strip 17. The member 22 also has a pair of slots 22^c extending 95 transversely, adapted to receive the wedges 23, which wedges also engage in the slots in strip 17. The member 22 is provided with lugs at one side in which small set screws 25 are threaded, the inner ends of which are 100 adapted to engage the wedges 23 and hold the same in position. The wedges 23 have square holes 23^a in their wide ends adapted to fit over the heads of set screws 25 so that the wedges can be used as wrenches for 105 tightening said screws 25.

It will be seen that when the strip 17 and member 22 is in position that the strip can be tensioned and the form drawn up to tight position by the use of wedges, as explained above in connection with Figs. 1 to 3. When the wedge is driven into place which holds the form in its final position, the set screw 25 can be tightened and the device thus securely locked in proper position. The member 22 presses evenly on the timbers 21 and the strip 17 exerts a stress centrally on the member 22. It is more or less common practice to use the additional members 21, and the arrangement shown in Figs. 4 and 5 115 120 is very convenient in connection with such additional members.

In Figs. 6, 7 and 8, a form is shown having the walls 15 and the vertical timbers 26 extending at the side thereof. These timbers may be either 2 x 4's or 4 x 4's, two timbers of the 2 x 4 type being shown in Fig. 6.

The strips 17 already described are used, one of these strips extending through and between the walls 15 adjacent each side of 130

the timbers 26. The member 27 is provided having a flat surface adapted to engage the outer side of the timbers 26 comprising flange 27^a having one or more holes there- 5 through to receive the nails 28 driven into the timbers 26 and member 27 has a portion 27^b extending at right angles at one end adapted to extend along one side of the timbers 26, which portion is formed with 10 a passage shown as a narrow slot 27^c which receives the end of strip 17. This portion 27^c has a pair of transverse slots 27^d extending therethrough and spaced differently from the slots in strip 17. The other end of member 27 has a side slot or opening 27^e through which passes a member 29 having a head portion 29^a at its outer side extending at each side of the opening 27^e. The member 29 also has a passage therethrough shown as 15 the narrow slot 29^b which receives the end of the other strip 17, this portion 29^b also having a pair of slots 29^c extending therethrough transversely of slot 29^b and spaced differently from the slots in strip 17. The member 20 29 also has a small lug projecting at one side, in which a rivet 30 may be placed, preventing member 29 from being moved out of opening 27^e and thus separated from member 27. The slots 29^c and the transverse 25 slots in portion 27^e are adapted to receive the wedges 20 which also pass through the slots in the strip 17. A member 31 is shown extending along the outer side of the timbers 26 at the other side of the form, which 30 member has a flange with one or more openings therethrough adapted to receive nails 32 driven into the timbers 26. The member 31 has a narrow slot at each end into which the end of strip 17 projects and said mem- 35 ber has a pair of holes 31^a at each side of its center through which a nail 33 may be inserted to pass through one of the slots 17^a in strip 17.

In operation of the device shown in Figs. 45 6 to 8, the strip 17 will be positioned as shown and the nails 33 dropped through slots therein in the member 31. The wedges 20 can then be successively driven into the members 27 and 29 and the strip 17 tensioned to bring the form up to tight position. The strip 17 will pull evenly on the timbers 26. It will be noted that the member 29 can be moved in the opening 27^e so that the device could be used with one 2 x 4 or one 50 of the members 26 as well as with two of the members or with a 4 x 4. When the member 29 is adjusted for a 2 x 4 the nails 33 will be inserted through the same holes 31^a. The successive take-up movements of the wedges 60 is clearly illustrated in Fig. 7.

In Figs. 9 to 13 the invention is illustrated as applied to a wall made up of the well known commercial metal sections. These sections are shown as 35 and are rectangular 65 in shape and as having a reinforcing angle

35^a at their outer sides, one portion of which projects outwardly and the other portion of which is disposed flat against the sheet metal member 35^b forming the surface of the wall. Said panels also are shown as having intermediate vertically extending reinforcing angle members 35^c. Such metal panels commercially have an angle bar 36 extending longitudinally thereof at their outer sides. In Fig. 10 a member 37 is shown having an 70 arm 37^a slightly spaced therefrom adapted to engage over the outwardly projecting web of the channel 36. This member 37 has a narrow slot 37^b therethrough, as shown in Fig. 9 through which one end of strip 17 75 passes. The strip 17 is shown as passing through a slot 38 formed between the engaging angles 35^a by having one side of the angle offset for a short distance, as shown at 35^d. The member 37 has a pair of slots 80 37^c extending therethrough transversely of a slot 37^b adapted to receive the wedges 20 which also pass through the slot 17^a in strip 17. With this structure it will be seen that the members 35 and 36 can be drawn up to 85 90 a tight position by the successive use of the wedges 20 in the slots 37^c and 17^a, as already described in connection with Figs. 1 to 2. The form can thus be tightly secured in proper position and the same can be taken up at any time desired. The friction on the wedges 20 will be sufficient to hold the same in proper position.

In Figs. 11 and 12 a member 40 is shown comprising spaced sides forming a slot 40^a 100 adapted to receive the end of the strip 17 having therein the slot 17^a. The sides of member 40 are connected by a web along one side, as shown in Fig. 9 so that said member is of channel shape in cross section. The 105 sides of this member are pierced by slots 40^b extending transversely of the slot 40 which are adapted to receive the wedges 20 which also pass through the slot 17^a, as shown in Fig. 12. One side of member 40 has a lug 110 projecting at right angles thereto which is riveted to one of the angles 35^a so that the device can be folded up longitudinally along side of the angle, as shown in the dotted lines in Fig. 11. Some standard metal sectional forms, like those illustrated, have clamping members pivoted to the angles 35^a and the member 40 could conveniently combine both the clamping member and the strip tensioning member. The ends of member 40 which embrace the adjacent projecting webs of the angles 35^a act to clamp these webs in assembled position. The strip 17 in the showing in Figs. 11 and 12 pass through a slot 115 35^c which is formed by offsetting the vertical flange of the angle 35^a a short distance.

With the structure shown in Figs. 11 and 12 it will be seen that the strip 17 can be tensioned and the members 35 tightly drawn 120 up to proper position.

- In Fig. 13, the member 41 is shown having end portions 41^a adapted to embrace the vertical webs of the pair of adjacent angles 35^a of two of the sections 35. The member 41 has a narrow passage 41^a adapted to receive the end of the strip 17 passing through a slot 35^c formed between the angles 35^a in the same manner described for the slot 35^c. The member 41 also has a pair of slots 41^b therethrough extending transversely to slot 41^a, which slots 41^b are adapted to receive the wedge members 20 which also pass through the slots 17^a in strip 17. With this structure it will be readily seen that the strip 17 can be drawn tight and the form placed in proper position by the successive use of the wedges 20 in member 41. In the showing in Figs. 9 to 13 it will, of course be understood that strips 17 may be equipped with similar devices on their other ends (not shown) or may be held in place merely by some member extending through one of the slots 17^a and engaging the outer side of the form.
- In Fig. 9, the member 42 is also shown having parallel sides connected at the bottom to form a slot 42^a. The member 42 has an offset flange 42^b at its end extending under and riveted to the horizontal web of the channel member 36. The slot 42^a is adapted to receive the end of the strip 17 having the slots 17^a therein, the strips 17 in this case being inserted through holes 35^b punched in the sheet metal 35^b. The member 42 is also provided with a pair of transverse slots 42^c extending through both sides thereof transversely to the slot 42^a. The slots 42^c are adapted to receive the wedges 20 which also pass through the slots 17^a and strips 17. The strip 17 and the member 42 are tightened, as has been previously described, by successive use of the wedges 20 in the slots 42^c. The member 42 is permanently connected to the angle 36.
- From the above description it is seen that applicant has provided a very simple and efficient form tie. The tie comprises few parts which are simple and inexpensive. The strips used will, as stated, remain in the wall and the other parts of the tie will be used over and over on different jobs, a new set of strips only being provided for each job. The device is adapted to be used with either wooden or metal forms and can be made to be either separate from or connected to parts of the latter. The invention has been amply demonstrated in actual practice and found to be very successful and efficient.
- It will, of course, be understood, that various changes may be made in the form, details, arrangement and proportions of the parts without departing from the scope of applicant's invention, which, generally stated, consists in a device capable of carrying out the objects above set forth, in the novel parts and combinations of parts disclosed and defined in the appended claims.
- What is claimed is:
1. A tie for a form having spaced walls having in combination, a strip adapted to extend through and between said walls and having elongated spaced slots therein, members adapted, respectively, to engage the outer sides of the form adapted to receive said strip, one of said members having slots extending transversely thereof, spaced a different distance apart than the slots in said strip, and wedges adapted to pass through the slots in said last mentioned member and the slots in said strip and draw and hold the strip in tight position.
  2. A tie for a form having walls and a member extending longitudinally thereof comprising a strip extending through and between said walls and having spaced slots therethrough extending longitudinally thereof, means at the exterior of one wall for holding one end of said strip, a member engaging said first mentioned member for receiving said strip and having slots extending therethrough adapted to align with and spaced a different distance apart than the slots in said strip, and wedges extending through the slots in said last mentioned member and strip and acting to draw and hold said strip under tension.
  3. A tie for a form having walls and a member extending longitudinally thereof comprising a strip adapted to extend through said walls and having spaced slots therethrough extending longitudinally thereof, a member engaging said first mentioned member adapted to receive said strip and having slots extending therethrough adapted to align with and spaced a different distance from the slots in said strip, said member having an arm extending substantially at right angles to its slotted portion adapted to be connected to said first mentioned member, and wedges adapted to pass through said slots in said second mentioned member and strip to tension said strip and hold the same under tension.
  4. A form tie having in combination, a strip with elongated spaced slots therein, a member adapted to engage the exterior of the form adapted to have one end of said strip pass therethrough and having slots extending transversely thereof, spaced a different distance apart than the slots in said strip, wedges adapted to pass through the slots in said member and the slots in said strip and draw and hold the strip in tight position, means for securing said member to the exterior of said form, and means for holding the other end of said strip.
  5. A tie for a form having walls and a member extending along the exterior thereof comprising a member adapted to engage said first mentioned member and having portions

- disposed at each side thereof, each of said portions having a passage extending longitudinally therethrough with transverse spaced slots extending therethrough transversely of said passage, strips of metal adapted, respectively to have their ends received in said passages and having slots therethrough spaced differently from the slots in said portions, wedges adapted to pass through the slots in said portions and strips and draw said strips tight in the form, and means for holding the other ends of said strips.
6. The structure set forth in claim 5, one of said portions being movable toward and from the other to accommodate different sizes of said first mentioned member.
7. A tie for a form having walls and a member extending longitudinally thereof comprising a strip extending through and between said walls and having spaced slots therethrough extending longitudinally thereof, means at the exterior of one wall for holding one end of said strip, a member engaging said first mentioned member for receiving said strip and having slots extending therethrough adapted to align with and spaced a different distance apart than the slots in said strip, wedges extending through the slots in said last mentioned member and strip and acting to draw and hold said strip under tension, whereby a continuous take-up can be had between said last mentioned member and strip, and means for holding said wedges in fixed position.
8. The structure set forth in claim 7, said last mentioned means comprising headed set screws threaded into said last mentioned member, said wedges having holes therein fitting said set screw heads whereby said wedges can be used as wrenches for said screws.
9. A form tie for a concrete form having spaced walls comprising a strip adapted to extend through and between said walls, means at the exterior of one wall securing one end of said strip, said strip having slots therethrough adjacent its other end, a member at the exterior of the other wall of said form through which said strip passes also having spaced slots therethrough, wedges passing through said member and strip for tightening said strip and form and holding the same in tightened position, the slots in said strip being spaced apart less than half the distance that the slots in said member are spaced apart.
10. A tie for a concrete form having spaced walls comprising a strip adapted to extend through and between said walls and
- having elongated spaced slots therein, a member at one side of the form holding one end of said strip, means at the other side of the form for tightening said strip and drawing the form to proper position and wedges disposed in said slots in said strip at the inner sides of the walls of said form for spacing said walls.
11. A tie for a concrete form having spaced walls comprising a strip adapted to extend through and between said walls and having spaced openings therethrough, a member at the exterior of one wall of the form for holding one end of said strip, means at the exterior at the other wall of said form for tightening said strip and drawing the form to proper position, and means co-operating with said slots for spacing said walls.
12. A clamp for a concrete form having spaced walls comprising an elongated member extending between said walls, means engaging said member at the inside of said walls to space the same, a member at the outer side of said form having spaced slots therein, and wedge means adapted to extend through said member and slots to tighten said elongated member and clamp said form.
13. A clamp for a concrete form having spaced walls comprising a member disposed at and engaging the outer side of said form, having spaced slots therethrough, an elongated member extending through said member and having slots therethrough spaced a different distance apart than the slots in said first mentioned member, wedge means adapted to pass through said member and slots therein to draw said elongated member into said first mentioned member and clamp said form and means engaging said elongated member and disposed at the inner side of the wall of said form.
14. A form tie or clamp having in combination, an elongated member having spaced openings therethrough, a member adapted to engage the exterior of the form adapted to have one end of said member pass therethrough and having spaced openings extending transversely thereof but spaced a different distance apart than the openings in said first mentioned member, wedges adapted to pass through the openings in said member to draw the elongated member into said second mentioned member, and wedges adapted to pass through the openings in said elongated member at the inside of the walls of the form, and means for holding the other end of said elongated member.

HOWARD O. McMILLAN.
